UNITED STATES PATENT OFFICE.

MYRON R. RANDALL, OF WAUPACA, WISCONSIN, ASSIGNOR OF ONE-HALF TO FRANCIS D. RANDALL, OF WAUPACA, WISCONSIN.

AIR GUN OR RIFLE.

Application filed February 26, 1923. Serial No. 621,401.

To all whom it may concern:

Be it known that I, MYRON R. RANDALL, a citizen of the United States, residing at Waupaca, in the county of Waupaca and 5 State of Wisconsin, have invented certain new and useful Improvements in Air Guns or Rifles, of which the following is a specification.

My invention relates to spring actuated 10 air guns, or rifles.

An important object of my invention is to provide a gun or rifle of the above mentioned character, so constructed that the maximum compression is obtainable with 15 a spring of a given strength, whereby the bullet is fired with the maximum force.

A further object of my invention is to provide means for effecting a substantially air tight joint between the barrel of the gun 20 or rifle and the air chamber, without obstructing or reducing the bore of the barrel, which would result in retarding the passage of the air through the same.

A further object of the invention is to provide a magazine air gun or rifle, with means 25 for automatically transferring the bullets from the magazine to the barrel, which means is extremely accurate in operation.

A further object of the invention is to provide an air gun or rifle so constructed that 30 the plunger actuating spring is placed under compression by a rearward movement of the compressing lever.

A further object of the invention is to 35 provide an air gun or rifle so constructed that the bullets are introduced into the rear end of the barrel, with an air chamber movable toward and away from such rear end, the plunger and spring being carried in the 40 air chamber and movable rearwardly with it as a unit whereby the spring is not compressed upon the rearward movement of the air chamber, thereby eliminating danger of injury when manually introducing the 45 bullets into the rear end of the barrel.

A further object of the invention is to provide an air gun or rifle of the magazine 50 type, having automatic means for preventing the placing under compression of the spring of the air compressing mechanism, when the last bullet has been transferred from the magazine to the barrel and fired from the barrel.

A further object of the invention is to provide means for indicating the number of 55 bullets contained within the magazine of the gun or rifle.

A further object of the invention is to so construct an air gun or rifle that a light trigger pull is obtainable with the maximum 60 safety against accidental discharge of the gun.

A further object of the invention is to provide an air gun or rifle of the above mentioned character capable of having a light 65 trigger pull, with the maximum safety against the accidental discharge of the same, with means to vary the lightness of the pull of the trigger.

A further object of the invention is to provide an air gun or rifle having reliable and simple means to automatically lock the trigger mechanism against operation, until released by the operation of a finger gripping part. 70

A further object of the invention is to provide a gun or rifle of the above mentioned character, having manually operated means which is adapted to be set to prevent the operation of the finger gripping part or 80 release, in operating the trigger locking means.

A further object of the invention is to provide an air gun or rifle having an element which is adapted for movement into 85 the rear end of the barrel to properly seat the bullet into such rear end.

A further object of the invention is to provide manually operated means to discontinue the feeding of the bullets from the magazine, at will, whereby the gun or rifle may be used as a single shot gun or rifle. 90

A further object of the invention is to provide graduated means for obtaining the selected or desired trigger pull. 95

A further object of the invention is to so construct the gun or rifle that its principal parts are positively operated, dispensing with the employment of springs, during such operation, as much as possible. 100

A further object of the invention is to provide a gun or rifle of the above mentioned character, so constructed that certain of the operating parts may be readily removed as a unit. 105

A further object of the invention is to

provide a gun or rifle of the above mentioned character, which is of simple construction, in consideration of the various functions to be performed, and their manner of performance.

A further object of the invention is to provide an air gun or rifle of high efficiency and which is accurate in firing, whereby the same may be successfully employed in shooting small game, and in target shooting.

Other objects and advantages of the invention will be apparent during the course of the following description.

In the accompanying drawings, forming a part of this specification, and in which like numerals are employed to designate like parts throughout the same,

Figure 1 is a side elevation of a gun or rifle embodying my invention,

Figure 2 is a central longitudinal section through the rear portion of a gun or rifle, certain of the operating parts being in elevation,

Figure 3 is a side elevation of the barrel and magazine of the gun, a portion of the magazine being in longitudinal section, for the purpose of illustration,

Figure 4 is a view similar to Figure 2, with the air chamber in the rear position, and the carrier elevated,

Figure 5 is a side elevation of the carrier removed,

Figure 6 is a central longitudinal section through the carrier, the operating parts being in elevation,

Figure 7 is a bottom plan view of the gun or rifle, with the fore arm removed, and parts broken away,

Figure 8 is an enlarged central longitudinal section through the forward portion of the receiver of the gun or rifle, parts broken away, and parts in elevation,

Figure 9 is a front end elevation of the carrier removed,

Figure 10 is a side elevation of the lever and associated elements for controlling the rearward movement of the trigger,

Figure 11 is a perspective view of the coacting control lever and trigger, parts broken away,

Figure 12 is an enlarged central longitudinal section through the plunger and associated elements, parts broken away,

Figure 13 is a side elevation of the bullet or follower engaging element included in the manually operated means for discontinuing the feeding of the bullets from the magazine,

Figure 14 is a side elevation of such means, showing the manually actuated element or finger piece,

Figure 14^a is a side elevation of a portion of the receiver, showing a slot therein,

Figure 15 is a side elevation of an ad-

justable pointer for regulating the trigger pull,

Figure 16 is an enlarged detail section taken on line 16—16 of Figure 15,

Figure 17 is a transverse section taken on line 17—17 of Figure 4,

Figure 18 is an enlarged side elevation of the engaging ends of the sear and trigger,

Figure 19 is an enlarged side elevation, parts in section, of the manually operated control device, coacting with the spring means of the trigger stop or lock,

Figure 20 is a side elevation of the slideable cylinder or sleeve of the spring means,

Figure 21 is a side elevation of the sub-frame,

Figure 22 is a plan view of the frame, and,

Figure 23 is a side elevation of a guide plate, having a cam slot.

In the drawings, wherein for the purpose of illustration is shown a preferred embodiment of my invention, the numeral 20 designates the barrel of the gun, and this barrel has its rear end portion 20' exteriorly reduced in diameter and is preferably screw-threaded, as shown at 21, to engage within a screw-threaded opening formed in a transverse disk or support-member 22, which is rigidly mounted within the forward portion of the frame or receiver 23.

This disk or support-member may be rigidly attached to the receiver by any suitable means, and may be brazed therein, if desired. The numeral 21', designates a second disk or support-member, which is rigidly mounted in the extreme forward end of the receiver 23 and has an opening 22', to receive the reduced portion 20'.

This reduced portion 20' forms a shoulder 23', with the forward portion of the barrel 20, as shown. The forward end of the receiver or frame 23 is preferably contracted, as indicated at 24, and is provided with an opening for receiving the barrel 20, as is usual in gun constructions. The receiver or frame 23 has a stock 25, suitably secured to a sub-frame. The numeral 26 designates the fore arm of the gun, which is preferably detachably mounted upon the lower portion of the receiver 23, near its forward end. The barrel 20 is provided at its forward end with a sight 27, of any well known or preferred type and is also equipped with an open rear sight 28, and a peep sight 29, at the rear end thereof, as shown. The numeral 30 designates a tube or magazine for holding the bullets, and this magazine or tube is arranged beneath the barrel 20, as shown. The forward end of this magazine is closed and is suitably attached to the barrel 20 while the rear end of the magazine extends into the contracted portion 24 of the receiver 23,

and passes through an opening 31, formed in the disk 21', and opening 32, formed in the

90

125

disk 22, as more clearly shown in Figure 3. It will be understood that this is the preferred manner of mounting the barrel and magazine within the receiver, for effecting a strong and rigid connection, but the invention is in no sense restricted to this particular type of mounting. The magazine 30 is preferably provided upon its exterior, with a longitudinal scale 29', for coaction with a thumb piece 176, to be described, to indicate the number of bullets in the magazine.

The upper portion of the receiver 23 is formed into a cylindrical guide 33, within which is mounted to freely reciprocate an air chamber or cylinder 34. The rear end of this air chamber or cylinder is provided with a cap 35, which is preferably screw-threaded thereon, and is provided with apertures 36, for the free passage of air into the chamber, rearwardly of the plunger or piston 37, to prevent the formation of vacuum within the air chamber. The cap 35 constitutes an abutment which is movable with the air chamber or cylinder 34, for engagement with a compressible coil spring, to be described. This plunger 37 is rigidly mounted upon a plunger rod 38, as more clearly illustrated in Figure 12. The detailed construction of the plunger will be described hereinafter. The plunger rod 38 slides within a guide sleeve or tube 39 which is carried by the cap 35, and preferably formed integral therewith. A main compressible coil spring 40 surrounds the plunger rod 38 and guide sleeve or tube 39, rearwardly of the plunger 37, as shown. This spring 40 is mounted within the air chamber, and is confined between the plunger 37 and the abutment 35 carried by the air chamber. The plunger rod 38 projects rearwardly through an opening in the cap 35 and is provided at its rear end with a sear engaging head 41, as shown.

The air chamber or cylinder 34 is adapted to move forwardly into close relation with the rear end of the barrel 20, and this chamber or cylinder is adapted to cover and uncover a main opening 42, formed in the top of the guide cylinder 33. The opening 42, affords access to the rear of the bore 43 of the barrel, whereby the bullets may be manually introduced into this bore, when desired. The bore 43 is uniform in diameter throughout its entire length.

The construction of the forward end of the air chamber or cylinder 34 will now be given, and for this purpose, attention is called particularly to Figures 2 and 12. The air chamber 34 is provided with a forward end or head 44, preferably formed integral therewith. This head is provided with a rearwardly extending tubular socket 45, integral therewith. The socket 45 is adapted to receive a tubular nipple or reduced extension 46, formed upon the extreme end of

the barrel 20. These parts have a close sliding fit. The numeral 47 designates a packing element or washer, which is preferably formed of fiber of medium hardness, but possessing a suitable yielding action. This packing element has an opening through which the tubular extension 46 projects, and the packing element is arranged rearwardly of the disk or support-member 22. The bore 43 of the barrel extends through the reduced extension 46, and is in communication with a bore 43', which passes through the socket 45, and associated shock absorbing elements, to be described. Particular attention is however called to the fact that a joint is effected between the head 44 of the air chamber 34 and the rear end of the barrel 20, which is air tight to the maximum extent, and this joint is effected without reducing the diameter of the bore of the barrel, or the bore 43', which is in effect a continuation of the bore of the barrel. This is important, as it provides the maximum compression of the air within the air chamber, and also offers the least resistance to the discharge of the air through the bore of the barrel, when the gun is being discharged.

The shock absorbing means which is arranged within the forward end of the air chamber 34, rearwardly of and adjacent to the head 44, to take the impact of the plunger or piston 37, embodies a rear washer 48, preferably formed of hard wood fiber, an intermediate washer 49, preferably formed of leather, and a forward washer 50, preferably formed of felt. The washers or elements 48, 49 and 50 are held against turning movement, in the forward end of the air chamber 34 by any suitable means, or by frictional engagement therein, and the bore or opening 43' is formed through the upper portions of these washers or elements. The guide cylinder 33 and the air chamber 34, with the elements carried therein, are preferably arranged eccentric with respect to the barrel 20, and this construction is advantageous as it eliminates the necessity of employing a high front sight.

The plunger 37 embodies a cylindrical body portion 51, having a sliding fit within the air chamber 34, and this body portion has the forward end of the plunger rod 38, secured thereto, as clearly shown in Figure 12. The body portion 51 carries a rear annular flange 52, provided with annular surface grooves 53, carrying lubricating rings 54, which may be made of felt, or any other suitable material. The body portion 51 is provided with a forwardly extending portion 55, which is diametrically reduced or contracted, and is adapted for the reception of the packing rings of the plunger or piston. I have found that these packing rings are of considerable importance, as I have

been able to obtain the maximum compression by the use of the same, combined with long wear, and the minimum friction. The numerals 56 and 57 designate rings or carriers, which are integral, and formed of steel. These rings or carriers are slipped upon the reduced portion 55 of the plunger, over the rear end thereof. The carrier 56 supports the split packing ring 58, preferably formed of cast iron, while the carrier 57 supports the split packing ring 59, preferably formed of hard fiber. Arranged forwardly of the carrier 56 is a solid packing ring 60, preferably formed of hard fiber. 10 The several rings are retained in place upon the reduced portion 55 by means of a head or cap 61, secured to the portion 55 by means of a screw 62 or the like. The precise construction of the piston and its packing means is important. I provide the solid packing ring 60, formed of fiber, as the same constitutes a piston guide for the plunger within the air chamber 34, and fiber will slide within the chamber with the least friction. 15 The split packing rings 58 and 59 are expandable and contractible within limits, and hence are adapted to accurately contact with the inner wall of the chamber 34, for effecting the maximum compression. A cast iron packing ring would be more suitable for producing the maximum compression, but would tend to produce friction and hence retard the proper movement of the plunger. The split fiber packing ring would 20 not produce as much compression as the cast iron packing ring but less friction. I have found that highly advantageous results are obtainable by employing two split packing rings, one of cast iron, and one of fiber, and 25 having their combined cross-sectional areas about equal to that of one packing ring, and hence I obtain a combination of the advantages of both types of packing rings, without the disadvantages of a full size ring of either material. It is of course obvious that 30 the invention is in no sense restricted to the precise form of packing shown and described.

One of the important features of my invention is the provision of means whereby the plunger actuated spring of the gun is compressed by a rearward movement of the compression lever. This means will now be described. The compression lever is designated by the numeral 62, and this compression lever is mounted between sides 63, depending from the guide cylinder 33, and integral therewith. The compression lever is pivotally supported between its ends by a pin 64, attached to the sides 63. At its rear end, the compression lever 62 is equipped with a hand loop 65, as shown. The compression lever 62 has pivotal connection at its forward end, as shown at 66, with a forwardly extending link 67, which is

provided at its forward end with an apertured knuckle 68, arranged between a pair of knuckles 69, and pivotally connected therewith by a pin 71. The knuckles 69 serve as a trip element, as will be more fully explained. These knuckles 69 are formed integral with a base or lug 72', which is rigidly secured to the lower portion of the air chamber 34, by any suitable means. 70

When the compression lever 62 has its lower end swung forwardly, its upper end is swung rearwardly and the air chamber 34 slides rearwardly within the guide cylinder 33. This rearward movement of the air chamber brings the sear-engaging head or element 41, in engagement with a self-releasing sear 72, to be next described. By the term "self-releasing sear" employed in the description and claims, I mean a sear which will be automatically moved outwardly by the action of the spring upon the plunger, to release the plunger, if not supported or held against such outward releasing movement, as distinguished from the ordinary type of sear which when engaging with the plunger or an element carried thereby, locks itself in such engagement, until positively moved in one direction for releasing such locking engagement. This sear 72 is pivoted upon a transverse pin 73, mounted in a cap 74, engaging and closing the rear end of the guide cylinder 33. This cap constitutes a part of a sub-receiver or frame and embodies forwardly extending sides 75, which are passed between the sides 63, and snugly engaging therewith. These sides carry the pin 64. These sides have openings 76, for receiving the pin 64, which serves to connect the forward ends of the sides 75 with the main sides 63. The numeral 77 designates a pair of bolts, Figures 1, 2, 4 and 21, which extend transversely through openings in the sides 63 and through openings 78 in the side 75, thereby securely locking the sub-frame to the main frame or receiver. The sear 72 is pivoted upon the pin 73, as above stated, and is provided at its free end, and above the pivot 73 with a resetting extension 79, which is adapted to be engaged by the head 41, and swung rearwardly by this head, in opposition to a plunger 80, compressing the spring 81. This plunger is slidable within a tube 82, formed in the cap 74, as more clearly shown in Figure 2. When the resetting extension 79 is swung rearwardly, as above stated, the forward end of the sear is swung upwardly to the reset position, as will be described. As more clearly shown in Figure 4, the sear 72 is provided with a substantially horizontal portion 83, and projecting forwardly in advance of the pivot 73 and provided with an upwardly projecting holding extension 84, which is adapted to engage in advance of the sear-engaging head 85 90 95 100 105 110 115 120 125 130

41. In Figure 4, the air chamber may be regarded as being shifted to the rearmost position, with the head 41 held behind the extension 84, and the compression lever 62 at the beginning of its rearward or compression stroke, for compressing the plunger actuating spring. The sear 72 embodies a relatively long forwardly projecting arm or lever 85, arranged beneath the pivot 73, and provided at its forward end with a trigger engaging foot 86. This foot has an inclined or beveled face 87, of substantial length, which is adapted to engage with an inclined face 88, of substantial length, formed upon the rear edge of a trigger 89. This trigger is mounted upon a pivot pin 90, which in turn is carried by the sides 75 of the sub-frame. The trigger extends downwardly beyond its pivot 90 into a finger engaging part 91, which is located within a trigger guard 92, formed in the compression lever 62. The trigger 89 has its upper end urged rearwardly by a plunger 92, slideable within a guide cylinder 93, which is arranged between the sides 75 of the sub-frame and rigidly secured thereto by any suitable means. The plunger 92 is urged downwardly by a compressible coil spring 94, and the plunger carries an upwardly extending rod 95, projecting above the cylinder 93. It will thus be seen that if the finger engaging portion 91 of the trigger is pulled rearwardly, the upper portion of the trigger 89 will move forwardly, and the forward end of the sear 72 will be released, whereby the sear will swing downwardly, and the head 41 will be released. This will permit of the discharge of the gun.

I provide an automatic safety device to prevent the trigger 89 being pulled for discharging the gun, until a grip releasing device has been actuated, which is instinctively effected in gripping the gun in shooting. This automatic safety device embodies a sliding stop 97, operating between the top of the cylinder 93, and a pin 98, extending transversely above the stop and attached to the sides of the sub-frame. The stop 97 has an inclined rear end 99, as shown. This stop 97 is provided with an arm 100, which is pivotally connected with a bell crank lever 101, pivoted upon a pin 102, attached to the sub-frame. The bell crank lever 101 has its lower arm 103, operating within the slotted end of a stationary guide cylinder 104, rigidly mounted in the sub-frame. This guide cylinder 104 slidably receives a reciprocating cylinder 105, within which is mounted a reciprocating plunger 106, urged downwardly by a compressible coil spring 107. The plunger 106 contacts with the arm 103 of the bell crank lever, and normally forces this arm downwardly, whereby the stop 97 is drawn to the right, over the rod 95, and the plunger 92 locked against up-

ward movement, and hence the trigger cannot be pulled rearwardly.

The sliding cylinder 105 has its upper end tapered or beveled, as shown. This upper tapered end is adapted to engage with beveled faces 108 and 109, formed upon the end of a latch 110, pivoted at 111. The beveled face 108 is higher than the beveled face 109, and hence when the latch is in the position shown in Figure 4, the spring 107 will hold the sliding cylinder 106 in the uppermost position. In this position, the arm 103 of the bell crank lever 101 will project downwardly beyond the lower end of the sliding sleeve 105. When the parts are so adjusted, the grip actuated releasing means may be employed to operate the automatic safety device for releasing the trigger. The grip releasing means embodies a lever 112, operating within a slot formed in the lever 62, and pivoted therein at 113. The lever 112 has its forward end swung upwardly by means of a spring 114. This lever is provided rearwardly of its pivot with a lateral extension, 115, which is of substantially the same diameter as the sliding cylinder 105, and is thereby adapted to enter the stationary cylinder 104 and force the arm 103 upwardly. It is thus seen that when the latch 110 is in the released position, as soon as the operator presses the lever 112 upwardly, the bell crank lever 101 will be swung forwardly upon its pivot, and the stop 97 moved out of the path of travel of the rod 95, thereby permitting of the upward movement of this rod and the pulling of the trigger.

If it should also be desired to lock the safety device against operation by the grip releasing means, the lever 110 will have its upper arm swung upwardly, whereby the lower face 109 will be brought into engagement with the tapered end of the sliding cylinder 105, and this sliding cylinder will be lowered sufficiently whereby its lower slotted end will project downwardly so that it will either be flush with the lower edge of the arm 103, or slightly below it. If the lever 112 is now moved inwardly, its lateral extension 115 will engage the lower end of the cylinder 105, which is now positively held against upward movement, and hence this extension cannot shift the arm 103 upwardly. The trigger will thus remain locked until the latch 110 is shifted downwardly.

As is well known, some sportsmen prefer a very light pull of a trigger, while others prefer much harder pull, and to meet these requirements, I have provided means for accurately adjusting the pull on the trigger. In accordance with my invention, the trigger 89, see more particularly Figures 4, 15, 16, 18, is provided upon its inner side with a lateral extension or lug 116, having a beveled face 117, adapted to be engaged by a tapered or beveled head 118, car-

ried by a bolt 119. This bolt is screw-threaded within a sleeve 120, and this sleeve is in turn screw-threaded within an opening 121, formed in one of the sides 63 of the receiver. The bolt 119 is provided in its outer end with a slot 122, so that it may be turned with respect to the sleeve 120, by means of a screw driver or the like. This is to provide a selected adjustment, at which the gun may be set, independently of the manual adjustment, to be described. The sleeve 120 carries a pointer 123, rigidly connected therewith, and extending radially therefrom, and this pointer is provided with a button 124, by means of which it may be conveniently turned. The pointer travels in proximity to a suitable scale 125, which is graduated to indicate the degree of lightness of the pull of the trigger desired. It is thus seen that when the pointer 123, Figure 1, is swung forwardly, the sleeve 120 will be turned counter-clock wise and moves outwardly with respect to the trigger 89, the bolt 119, moving with it. The tapered head 118 is thus moved outwardly and the upper end of the trigger 89 accordingly permitted to move rearwardly a greater distance. The inclined face 88 will now move rearwardly in engagement with the inclined face 87 of the sear, and hence the extent of contacting surfaces of these faces is increased. It should be remembered that the entire force of the spring 40, under compression, is transmitted to these contacting faces 87 and 88, and it will be seen that the frictional engagement between these faces will vary with the extent of the contacting areas of the faces. Further, the faces 87 and 88 being inclined, as shown, the trigger must move the sear 72 upwardly a greater distance, as the engaging surfaces of the faces 87 and 88 are inclined. For these two reasons, the pull upon the trigger 89 varies, in accordance with the distance that the upper end of the trigger is permitted to travel, when engaging with the sear. It is thus seen that the desired trigger pull may be obtained, by manually adjusting the pointer 123 with respect to its scale 125, without the employment of a screw-driver, or other implement.

My gun is designed to be used as a single shot gun or as a repeater. To accomplish this, I provide means for transferring the bullets from the magazine to the rear end of the barrel. This transferring means embodies a pivot or laterally movable carrier 126. The carrier embodies a pair of sides 127, see particularly Figures 4, 5, 6 and 17. Disposed between the forward ends of these sides 127 is a casing or block 127', rigidly secured thereto. The sides 127 are provided at their rear ends with upwardly projecting knuckles 132, and each of these knuckles are pivotally connected with the side 63,

by means of a shoulder bolt 133, which does not project inwardly beyond the knuckle.

It will be understood that the knuckles 132 are arranged outwardly of the path of travel of the knuckles 69 and 70, and the lug 72. The sides 127 of the carrier are provided at the rear ends with cam extensions 134, the upper edges of which are adapted to engage with the knuckle 69, which functions as a trip element. As clearly shown in Figure 4, when the air chamber 34 is moved rearwardly sufficiently, the knuckle 69 will ride over the cam extension 134 of the carrier, and swing the carrier vertically within the receiver, upon its pivot, causing the forward end of the carrier to move to its uppermost position, adjacent to the rear end of the barrel 20. When in this uppermost position, the forward edges or corners of the sides 127 contact with the inner wall of the guide cylinder 33 of the receiver Figure 17, and hence the carrier is positively held against movement upon its pivot, at this time, and during the period that the ejector is being actuated for introducing the bullet into the rear end of the barrel. The carrier is therefore positively actuated and positively held against improper movement, and the movement of the carrier, or the holding of the same, is not effected by means of springs, or other unreliable agencies. The sides 127 of the carrier are provided near their forward ends with cam edges or faces 135, which are adapted to move upwardly into the path of travel of the forward end of the air chamber 34, when the air chamber is in the rear or retracted position. Now, when the air chamber is being brought forwardly to have an air tight connection with the rear end of the barrel, the forward end of the air chamber riding over the cam surfaces 135, will swing the forward end of the carrier downwardly, the lower side of the air chamber finally riding upon the horizontal edges or faces 136, of the sides, which will serve to positively hold the carrier in the lowered position, while the air chamber is in the forward position. The sides 127 are provided with straight longitudinal slots 137, within which is slidably mounted the ends of a transverse pin 138, one end of this pin operating within a guide slot 139, formed in a plate 140, secured to one of the sides 63. The guide slot 139 embodies a rear inclined portion 141 and a forward approximately horizontal portion 142. It will be seen that as the pin 138 moves rearwardly into the inclined portion 141 of the slot, it will aid in swinging the carrier downwardly, and as it moves forwardly into the upper or horizontal portion 142 of the slot, it will aid in swinging the carrier upwardly, and in holding the same in the elevated position. The principal function of the pin 138 is to actuate the keeper and ejector elements sup-

ported by the carrier, as will be hereinafter explained. The pin 138 is rigidly mounted upon the forward end of a link 143, which link extends rearwardly and has its rear end 5 preferably forked for straddling a vertical projection 144, formed upon the forward end of the link 67 and pivotally connected with this vertical projection, as shown at 145. It is thus seen that when the lever 62 10 is moved rearwardly for advancing the air chamber, the link 143 and its pin 138 are moved forwardly, for a purpose to be described.

The casing or block 127' of the carrier, 15 has a pocket 128' for receiving the bullet 146. This socket holds therein a sleeve 147, rigidly secured to the same, and this sleeve has the forward portion of its bore spherically curved, as indicated at 148, which constitutes a seat or stop for the bullet, while 20 the rear portion of the bore, as indicated at 149, is tapered and flared rearwardly. This provides a knife edge 150, which forms a combined guide and fulcrum for the ejector 25 or plunger 151, which is also mounted within the casing 127'. It might be stated at this point that the ejector is adapted to be shifted forwardly beyond its casing 127', for a substantial distance, so that it will introduce 30 the bullet well into the nipple or extension 46 of the barrel 20, so that there can be no liability of the bullet not being properly introduced into the barrel. The ejector or 35 plunger 151 is pivotally connected, at 152, with the upper end of a vertical lever 153, which is pivotally mounted between its ends, as shown at 154. The lever 153 is pivotally connected at its lower end, at 155, with a link 156, which link, as more clearly shown 40 in Figure 6, is provided at its rear end with a head 157. This head carries a screw or 45 guide element 158, sliding in one of the longitudinal slots 137. This screw simply serves as a guide means for the rear end of the link 156, to prevent it from moving laterally with respect to the carrier.

The numeral 159 designates a latch, which is arranged upon the inner side of the head 157, Figure 6, and pivoted thereto at 160. 50 This latch carries a laterally projecting pin or stud 161, which is adapted to enter a notch 162, formed in the side 127. When the pin 161 is in the notch 162, the link 156 is locked against longitudinal movement 55 with respect to the carrier. The forward end of the latch 159 is urged downwardly by means of a spring 163, which tends to force its rear end upwardly. The latch 159 is provided with a rear cam or trip portion 164, 60 which is adapted to project upwardly across the slot 137, in advance of the head 157. This latch is also provided with a shoulder 65 165, which is adapted to extend across the slot when the forward end of the latch is elevated. With this explanation in mind,

it will be seen that when the link 143 moves rearwardly, with the rearward movement of the air chamber, that the pin 138 will travel rearwardly in the slots 137 and this pin 138 will first engage the upstanding cam element 70 or trip 164, first turning the latch 159 upon its pivot, whereby the pin 161 is withdrawn from the notch 162. This will release the link 156 so that it may move longitudinally with respect to the carrier. The further 75 rearward movement of the pin 138 brings the same into engagement with the rear end of the head 157 of the link, and the link will therefore be shifted rearwardly, until the guide pin 158 engages the rear end wall 80 of the slot 137. During this rearward movement of the link 156, the lever 153 is turned upon its pivot, and the ejector or plunger 151 is moved forwardly into the rear end of the barrel. When the pin 138 starts on its 85 forward movement, it engages with the shoulder 165, now arranged in its path of travel, and the pin will therefore move the link 156 forwardly, until the pin 161 reaches the notch 162, at which time the pin will 90 enter this notch and the link will then be locked against longitudinal movement. This movement of the link 156 will move the ejector or plunger 151 rearwardly.

In order that the bullet 146 may not accidentally discharge from the recess or pocket 128', when fed therein, by means to be described, I provide a keeper 166 which is pivoted within the casing 127' at 167. This keeper has an upwardly extending lateral tongue 168, which when elevated, is adapted to project a slight distance into the bore or the pocket or recess 128', sufficiently, to positively prevent the bullet from moving forwardly out of the pocket, until the keeper is lowered. The keeper has its forward end or lip 168 urged upwardly by means of a spring 169. The keeper is provided with a rearwardly extending tail 170, provided with cam surfaces 171 and 172. The cam surface 171 normally extends upwardly and transversely across the slot 137, and hence when the pin 138 moves forwardly, it engages the cam surface 171, and forces the rear end of the keeper 166 upwardly, moving the tongue 168 downwardly. It will be thus seen that when the carrier has its forward end lowered, so that the pocket or recess 128' is adjacent to the rear discharge end 100 of the magazine 30, the tongue 168 of the keeper will be in the open or lowered position, thus permitting of the bullet properly entering the pocket or recess. It is also necessary to provide means to move the tongue 168 downwardly, out of the pocket, 105 before the ejector or plunger 151 has moved forwardly sufficiently to push the bullet 146 past the tongue. To accomplish this, I provide the lever 153 with a lateral extension 173, at its lower end, which lateral ex- 110 115 120 125 130

8
 tension, engages over the cam face 172. Therefore, as soon as the ejector lever 153, has its lower end moved rearwardly, it rides along the cam face 172, and swings the forward end of the keeper downwardly. The parts are so timed in operation, that the tongue 168 will be moved downwardly out of the bore of the pocket or recess, before the bullet is moved forwardly sufficiently to contact with the tongue. Of course when the lever 153 is moved forwardly, to retract the ejector or plunger, the spring 169 elevates the tongue 168 into the bore of the pocket or cylinder.

10 15 The magazine 30 is constructed to hold a plurality of bullets 146, the number being determined by the capacity of the magazine. These bullets are not fed into the pocket or recess 128' by gravity, but are positively fed therein. To accomplish this, a carriage 174, Figure 3, is slidable within the magazine 30, and this carriage is provided with a radial extension 175, carrying a thumb piece 176, by means of which the carriage 20 may be advanced. A rod 177, preferably rigid, is secured to the forward end of the carriage and passes into a compressible coil spring 178, and serves to prevent the buckling of this spring, whereby the spring could 25 not improperly move out of the lateral opening 179, upon being compressed. This opening 179 is provided for the feeding in of the bullets. Secured to the opposite or rear end of the carriage 174 is a suitably resilient element 180, which I have found may be advantageously constructed of a piece of steel music wire. I have this wire 30 35 40 45 50 55 60 65 70 75 80 85 90 95 100 105 110 115 120 125 130 resilient element 180, which I have found may be advantageously constructed of a piece of steel music wire. I have this wire 180 resilient, in order that it may conform to the curvature of the rear part 30' of the magazine. At its rear end, the wire 180 carries a cylindrical head 181, which has substantially the same diameter as the bullet. The numeral 182 designates a spherical head, which is slightly spaced from the cylindrical head and is rigidly connected therewith by means of a shank 183. The cylindrical head 182 is preferably of the same diameter as the bullet being used in the gun.

45 50 55 60 65 70 75 80 85 90 95 100 105 110 115 120 125 130 The numeral 184 designates an automatic bullet stop element, for the magazine. This element is pivoted at its forward end, by a pin 185, carried by the sides of the receiver, and a spring 186 is provided to swing the stop element upwardly. This stop element is provided between its ends with an upwardly projecting bullet engaging part or finger 187, having a curved pocket 188 formed therein, and adapted to snugly engage with the bullet. The finger 187 moves vertically through a slot 189 in the curved portion of the magazine. The stop element 184 extends rearwardly beyond its finger 187 and has an inclined face 190, arranged beneath and in alignment with the forward end of the keeper 166. The arrangement is such that when the keeper 166 is moved downwardly, for withdrawing the tongue 168 from the bullet receiving pocket, the stop element 184 is simultaneously moved downwardly and the finger 187 is withdrawn from the bore of the magazine. The reason for this operation will be readily understood, when it is seen that the bullet must be free to pass into the pocket when the keeper 166 is depressed, and the rear-most bullet in the magazine must be locked against moving out of the magazine, as the carrier starts upon its upward travel, the keeper 166 moving upwardly prior to this upward movement of the carrier. Hence, the bullet within the pocket of the carrier is securely held against outward movement, and the next bullet in the magazine is held against discharging movement from the magazine, at about the time that the carrier starts upon its upward movement.

As is well known, it is very detrimental to an air gun to shoot the same when a bullet is not within the barrel, which is ordinarily termed snapping the gun. To prevent this, I provide automatic means for preventing the placing of the plunger actuating spring under compression, when the last bullet is fed from a magazine, and introduced into the barrel and fired from the barrel, while the gun is being used as a repeater. This means embodies a rearwardly projecting extension or tail 191 of the stop element 184, which is arranged in the plane of a longitudinally extending lever 192. The lever 192 is mounted upon a pivot element 193, secured to the wall of the receiver. The forward end of the lever 192 is provided with a fork 194, which engages upwardly beneath the rear end of the tail 191, while a spring 195, urges the forward end of the lever 192 upwardly. The rear end of the lever 192 has a lateral extension stop 196, which is adapted to be moved into and out of the path of travel of a lateral extension 197, formed upon the upper end of the trigger 89. It should be stated at this point that the stop 196 is out of the path of travel of the trigger, when the rear end of the lever 192 is in its upper or lower position, and is disposed in the path of travel of the same, only, when the lever is in the intermediate position. When the keeper 166 is moved downwardly for releasing the bullet from its pocket, the stop element 184 is moved to the lowermost position, and hence the rear end of the lever 192 is moved to the uppermost position. When a bullet is positioned within the magazine 30, above the recess 184, or when the spherical head 182 is in this position, the stop element 184 is adapted to move upwardly to its highest position, upon the upward movement of the carriage, and hence

the lever 192 will have its rear end moved downwardly to the lowermost position. Under both of these conditions, the stop 196 will clear the stop 197.

Assuming that the last bullet from the magazine has been fed into the pocket of the carrier, and the carrier has been elevated and this bullet transferred to the rear end of the barrel, then, the spherical head 182 will be held by the recess 188 with the stop 184 elevated. Prior to the firing of the last bullet, the carrier is again moved to lowermost position, and when this occurs, the stop element 84 is again depressed, releasing the spherical head 182, which has been held by the stop element as was previously done with the bullets. This spherical head now moves rearwardly slightly toward the pocket, and projects rearwardly beyond the rear edge of the finger 187, but not rearwardly sufficiently to enter the pocket. This extreme rearward movement of the spherical head 182 brings the forward end of the cylindrical head 181 over the forward edge of the recess 188, whereby the stop element 184 is held in the intermediate position. The rearward movement of the spherical head 182 is defined or limited by the extension 175 engaging with the rear end wall 175 of the slot in the magazine. When this occurs, the stop 196 is arranged rearwardly of and in advance of the path of travel of the extension or stop 197 of the trigger. Now, when the last bullet is fired, and the operator again attempts to shoot the gun, it will be found that the plunger actuating spring cannot be placed under compression, and this is effected because the upper end of the trigger 89 cannot move rearwardly sufficiently to effect a locking engagement with the forward end of the sear 72. This sear is self-releasing, but not self-locking. The lever 62, may now be swung forwardly and rearwardly, with no other result than the reciprocation of the air chamber without compressing the spring.

I also provide means whereby the feeding of the bullets from the magazine may be dispensed with, when desired, so that the gun may be used as a single shot gun, and also so that it may be used as a single shot gun when the bullets are exhausted from the magazine. This would also enable the bullets to be retained in the magazine, as a reserve, while the gun was used as a single shot gun.

This means is manually operated, and embodies a lever 198, pivoted at its lower end upon the exterior of the receiver, as shown at 199. At its upper end, this lever has a milled thumb piece 200. This lever 198 has pivotal connection at 201 with a link 202. This lever has a lower cam extension 203, arranged above and engaging a stationary shifting element 204. When the link 202 is urged forwardly, the cam extension 203 riding over the stationary element 204 simultaneously shifts the forward end of the link laterally or upwardly. This lateral shifting movement causes a shoulder bolt 205 to be withdrawn from a lateral notch 206 of a slot 207, formed in the wall of the receiver. The shoulder bolt 205 is mounted within a longitudinal slot 208 in the link 202. This slot 208, permits of the initial movement of the link 202 forwardly, prior to the release of the shoulder bolt 205. This shoulder bolt is also adapted to engage within a lateral depression 209 of the slot 207. The shoulder bolt 205 is rigidly mounted upon a magazine cut off stop element 210, which is provided with a lateral extension or tongue 211, operating in the slot 189 of the magazine. The extension or tongue 211 is arranged in slidable relation to the finger 187, upon one side thereof. The magazine cut off stop element 210 is provided with a longitudinal slot 212, receiving transverse pin 185, which pivotally supports the element 210 and also permits of its forward longitudinal movement. Hence, when the lever 198 is moved forwardly, the extension 211 is first shifted upwardly to engage behind the bullet or the spherical head 182, as the case may be, and when the forward movement of the lever 198 is completed, this bullet or spherical head is shifted forwardly sufficiently, whereby the bullet or head 182 is shifted entirely forwardly of the finger 187. Hence, the stop element 184 may swing forwardly to the uppermost position, and there is no liability of the lever 192 restricting the rearward movement of the trigger. With the parts thus adjusted, the air chamber may be moved rearwardly and this will uncover the main opening 42 in the guide cylinder and a bullet may be manually introduced into the rear end of the barrel. The sear will now lock the plunger rod in the rear position, and upon the rearward movement of the lever, the plunger actuating spring will be compressed. The bullet may now be fired, as is obvious.

It might be pointed out that when the gun is used as a single shot gun, the lever 62 is moved forwardly sufficiently to cause the air chamber to clear the opening 42, at which time the bullet may be manually inserted into the rear end of the barrel. Upon completing the forward movement of this lever, the carrier will move upwardly, and the plunger or ejector supported thereby will move into the rear end of the barrel and properly seat the bullet, as occurs when the gun is used as a repeater. When the cylinder is again moved forwardly and the spring placed under compression, of course the carrier descends, as already described. The operation of the gun or rifle as a repeater is as follows:

The lever 198, Figures 1 and 14, being in the rear position, the bullets are free to be fed from the magazine 30, in a manner to be described. Starting with the compression lever 62 in the closed position, the air chamber 34 will be in the forward position, and the carrier will be in the lowered position, as more clearly illustrated in Figures 2 and 8. The link 143 is in the forward position and its transverse pin 138 is now engaging the face 171 of the cam element or tail 170, of the keeper 166. This keeper is now held lowered, and its face 190 engages the face of the automatic magazine stop element 184, whereby its part 187 is held depressed. The spring pressed follower within the magazine urges the bullets rearwardly, and the rearmost bullet is shifted into the pocket of the carrier, while the rearward movement of the next bullets is prevented by engagement with the bullet in the pocket. When the compression lever 62 is now swung forwardly upon the loading movement, the link 143 moves rearwardly and the keeper 166 is released, and automatically swings upwardly by virtue of its spring and a part of this keeper now projects in advance of the bullet within the pocket, securely retaining the bullet therein. Simultaneously with this movement of the keeper, the automatic stop element 184 moves upwardly by virtue of its spring action and the next rearmost bullet is engaged within the pocket 188 and positively held against rearward movement from the magazine. It is thus seen that at about the time the carrier begins to rise toward the barrel, the bullet within the pocket is securely held therein and the bullets within the magazine prevented from discharging therefrom. The rearward movement of the air chamber 34 brings the knuckles 69 in engagement with the upper inclined surfaces of the tail or cam elements 134 of the carrier, automatically effecting the upward movement of the carrier, whereby the pocket holding the bullet is brought into registration with the bore of the barrel, at the rear end of the barrel. A little after this registration is effected the transverse pin of the link 143 engages with the latch device carried by the link 156, releasing the latch device, and engaging the shoulder 157 of the link 156, shifting such link rearwardly, and advancing the ejector or plunger 151. As clearly indicated in dotted lines in Figure 8, this plunger will now push the bullet from its pocket and force the same into the rear end of the barrel. The plunger will project into the barrel for a substantial distance, whereby the bullet will be well seated in the rear end of the barrel. The compression lever 62 will now start upon the rear or compression stroke. The first action is the bringing of the transverse pin 138 of the link 143 into engagement with

the shoulder 138 of the latch 159 carried by the link 156, and this link will be moved forwardly until the pin 161 of the latch drops into the notch 162, at which time the link 156 is again locked against longitudinal movement. This retracts the ejector or plunger 151, and further forward movement of the air chamber 34 brings its forward end into engagement with the cam faces 135 of the carrier, returning the carrier to its lowered position. The keeper, ejector, and automatic magazine stop element are restored to the positions previously occupied, as above explained, and as shown in Figure 8. When the air chamber is shifted to the rearmost position, as above stated, the head or extension 41 of the plunger rod engages behind the holding part 84 of the self releasing sear 72, the sear being swung upwardly by the head 41 contacting with the extension 79. When the forward end of the sear moves upwardly the spring pressed plunger 92 swings the trigger upon its pivot and the upper end of the trigger moves toward the sear. This brings the engaging faces 88 and 87 into contacting relation. The plunger rod is therefore held against forward movement while the air chamber is advanced, and hence the plunger actuating spring is placed under compression. The instant the engagement is effected between the faces of the trigger and sear, the safety stop element 97 moves rearwardly, and engages above the plunger rod 94, and the trigger is locked against pulling movement. When the compression lever 62 has completed its rearward movement, the pivot 66 between the link 67 and lever 62, is brought slightly outwardly of the pivot 64 of the compression lever, or out of alignment therewith, and this serves to lock the lever 62 and associated elements in the closed position, with the lever contacting with or adjacent to the stock 25. This lever will now retain the finger release element or lever 112 in proximity to the lever 103, and when the operator grips the stock, in the act of pulling the trigger, the release element or lever 112 will move the stop element 97 forwardly, allowing the plunger 92 to rise, so that the trigger may be pulled. If it should be desired to prevent the pulling of the trigger, when the stock is gripped in the act of shooting the gun, the manually operated safety element 110 is swung upwardly, and this will depress the sliding cylinder 107, causing it to move downwardly within the guide 104, so that its lower end will project flush with or below the arm 103 of the lever 101, constituting a stop for preventing the extension of the lever 112 from actuating the lever 101. The trigger will therefore remain locked against pulling movement until the manually operated safety element is shifted downwardly. The adjustment of the lightness of the pull of

the trigger, has been explained fully hereinbefore, it being sufficient to state that the lightness may be varied or increased from a selected fixed lightness to a harder pull, 5 by moving the lever 123 forwardly, and the adjusted pull can be read from the scale in proximity to the pointer or lever. The gun or rifle may be used as a single shot gun or rifle by shifting the lever 198 forwardly, 10 which causes the manually operated stop element 210 to first rise within the magazine and then move forwardly therein, carrying forwardly with it the bullet or bullets or the spring pressed follower. When used as 15 a single shot gun or rifle, the bullet is introduced manually by the fingers through the opening 42 of the receiver into the rear end of the barrel. A particular advantage in my construction is that while the gun is thus 20 being loaded the air chamber is in the rear position, and when in the rear position the plunger actuated spring is not under compression, and hence there is no liability of the air chamber driving forwardly upon 25 the fingers.

It is to be understood that the form of my invention herewith shown and described is to be taken as a preferred embodiment of the same, and that various changes in the 30 shape, size, and arrangement of parts may be resorted to, without departing from the spirit of my invention or the scope of the subjoined claims.

Having thus described my invention, I 35 claim:

1. In a gun or rifle, a barrel, a receiver connected with the barrel, an air chamber 40 slideable within the receiver, a plunger within the air chamber, a compressible coil spring within the air chamber at the rear of the plunger, an abutment carried by and movable with the air chamber and engaging with the spring within the air chamber, a plunger rod connected with the plunger and 45 extending rearwardly therefrom exteriorly of the air chamber and provided with a holding element, a sear pivotally connected with the rear portion of the receiver and having a holding element to engage with the first named holding element, the holding 50 element of the sear being arranged in advance of the pivot point of the sear whereby the forward movement of the plunger tends to shift the sear to the releasing position, 55 and a trigger engaging the sear at a point remote from the holding element for controlling the movement thereof toward the releasing position.

2. In a gun or rifle, a barrel, a receiver 60 connected with the barrel, an air chamber slideable within the receiver, means to move the air chamber, a plunger within the air chamber, a compressible coil spring within the air chamber at the rear of the plunger, 65 an abutment carried by and movable with

the air chamber and engaging with the spring, a plunger rod connected with the plunger and extending rearwardly therefrom and provided with holding means, a sear pivotally connected with the receiver 70 and adapted to engage with the holding means of the plunger rod when it is shifted rearwardly, said sear being so constructed that it is shifted outwardly to a releasing position upon the forward movement of the 75 holding means of the plunger rod, and a trigger coacting with the sear for controlling the movement of the same toward the releasing position.

3. In a gun or rifle, a barrel, a receiver 80 connected with the barrel, an air chamber slideable within the receiver, means to move the air chamber, a plunger within the air chamber, a compressible coil spring within the air chamber to drive the plunger forwardly, an abutment carried by and movable with the air chamber and engaging the rear portion of the spring, a plunger rod connected with the plunger and extending 85 rearwardly therefrom and having holding means near its rear end, a sear pivotally connected with the receiver and adapted to engage with the holding means of the plunger rod when it is shifted rearwardly, 90 said sear being so constructed that it automatically tends to move laterally away from the holding means for releasing the same unless held against such lateral movement, and a trigger coacting with the sear for controlling the outward lateral movement of 95 the same.

4. In a gun or rifle, a barrel, air compressing mechanism associated with the barrel embodying a spring actuated plunger, means to control the active movement of 100 the plunger embodying a self-releasing sear pivoted near one end and provided near its pivot with a holding element, and means supporting the sear against movement near its free end at a point sufficiently remote from the holding element whereby the pressure is proportionately reduced at the point of engagement with the releasing means.

5. In an air gun or rifle, a barrel, air compressing mechanism associated with the barrel embodying a plunger having an engaging part, a self-releasing sear adapted to engage with said engaging part and to automatically release said part when the sear is not held against releasing movement, and releasing means to normally prevent the releasing movement of the sear and engaging with said sear at a point spaced a greater distance from the pivot of the sear than the point of engagement between the sear and said engaging part whereby the pressure is proportionately reduced at the point of engagement with the releasing means.

6. In an air gun or rifle, a barrel, a cylinder associated with the barrel, a plunger 130

within the cylinder having a plunger rod provided near its rear end with a holding element, a spring to move the plunger forwardly, a self-releasing sear arranged rearwardly of the plunger rod and embodying an arm pivotally supported near its rear end, said arm being provided at a point in advance of its pivot with a transversely extending holding element for engagement 5 with the holding element of the plunger rod, said arm being also provided with a lateral resetting extension arranged in the path of travel of the rear end of the plunger rod, and a trigger having engagement 10 with the forward end of the arm whereby such engagement is at a point remote from the holding element of the arm.

7. In an air gun or rifle, a barrel, a receiver connected with the barrel, an air chamber slidably longitudinally within the receiver, a plunger within the air chamber, a compressible coil spring within the air chamber at the rear of the plunger, an abutment carried by the air chamber and movable with it and engaging the rear portion of the spring, a plunger rod secured to the plunger and extending rearwardly of the air chamber and having a holding element, a self-releasing sear arranged rearwardly of the air chamber and embodying a pivotally supported arm, said arm being provided with a holding element arranged upon one side of its pivot, and a resetting element disposed in the path of travel of 25 the plunger rod, and a trigger engaging the arm at a point remote from the holding element of the arm.

8. In an air gun or rifle, a barrel, a receiver carrying the barrel, spring actuated air compressing mechanism carried by the receiver for coaction with the barrel, a movable sear for controlling the operation of said mechanism, a movable trigger, said trigger and sear having engaging faces, a sleeve arranged near the trigger and extending transversely of the same and having screw threaded engagement with a part of the receiver, a tapered stop arranged transversely in the path of travel of the trigger 40 and extending into the sleeve and having screw threaded engagement therewith, and a pointer arranged upon the exterior of the receiver and connected with the sleeve for turning it, said receiver having a scale for coaction with the pointer.

9. In an air gun or rifle, a barrel, a receiver carrying the barrel, spring actuated air compressing mechanism carried by the receiver for coaction with the barrel, a movable sear for controlling the operation of said mechanism, a movable trigger for controlling the operation of said sear, a spring pressed plunger engaging a part of the trigger for moving its lower end forwardly, a 45 stop element movable into and out of the

path of travel of the plunger, spring means to shift the stop element in one direction into the path of travel of the plunger, and manually operated means separate from the stop element to move the stop element in an opposite direction out of the path of travel of the plunger.

10. In an air gun or rifle, a barrel, a receiver carrying the barrel, spring actuated air compressing mechanism carried by the receiver for coaction with the barrel, a movable sear for controlling the operation of said mechanism, a movable trigger for controlling the operation of said sear, a spring pressed plunger engaging a part of the trigger for moving its lower end forwardly, a stop element movable into and out of the path of travel of the plunger, a pivoted lever connected with the stop element, yielding means engaging one end of the lever to move it in one direction, and a pivoted lever adapted to be arranged near said lever and having a part movable into engagement with the end of the first named lever, the last named lever being adapted to be manually operated.

11. In an air gun or rifle, a barrel, a receiver carrying the barrel, spring actuated air compressing mechanism carried by the receiver for coaction with the barrel, a movable sear for controlling the operation of said mechanism, a movable trigger for controlling the operation of said sear, a spring pressed plunger engaging the trigger, a stop element movable into and out of the path of travel of the plunger, a pivoted lever connected with the stop element, a guide casing, a sleeve slidably in the guide casing and having its lower end adapted to be brought into engagement with the pivoted lever, a plunger slidably within the sleeve, a spring arranged within the sleeve behind the plunger, a manually operated element for adjusting the movement of the sleeve in one direction, and a manually operated releasing element having a part adapted to be brought into engagement with the pivoted lever.

12. In an air gun or rifle, a barrel, a receiver carrying the barrel, a reciprocating air chamber within the receiver for coaction with the barrel, a plunger within the air chamber, a plunger rod connected with the plunger, a spring mounted entirely within the air chamber and having its rear end engaging a part of the air chamber as an abutment to urge the plunger forwardly, means for engaging the plunger rod holding it against forward movement when the air chamber is moved forwardly so that the spring is compressed, a magazine associated with the barrel for holding a plurality of bullets, a pivoted carrier connected with the receiver for transferring bullets from the magazine to the barrel, said carrier having a

cam portion to be engaged by a part of the air chamber upon its rearward movement to swing the carrier upwardly and having a second cam portion to be engaged by a part 5 of the air chamber upon its forward movement for swinging the carrier downwardly, and means for moving the air chamber.

13. In an air gun or rifle, a barrel, a receiver carrying the barrel, a movable air chamber carried by the receiver for coaction 10 with the barrel, a plunger within the air chamber, a spring within the air chamber to urge the plunger forwardly, an abutment carried by the air chamber and movable 15 with it and engaging the rear end of the spring within the air chamber, means for holding the plunger in the rear position to compress the spring as the air chamber is moved forwardly, a magazine associated 20 with the barrel for holding a plurality of bullets, a pivoted carrier connected with the receiver for transferring the bullets from the magazine to the barrel, means to swing the carrier upon its pivot, and means to 25 move the air chamber.

14. In an air gun or rifle, a barrel, a magazine associated with the barrel, a receiver carrying the barrel, a movable air chamber carried by the receiver for coaction 30 with the barrel, a plunger within the air chamber, a spring within the air chamber to urge the plunger forwardly, an abutment carried by the air chamber to move therewith and engaging the rear end of said 35 spring, means for holding the plunger in the rear position to compress the spring, a carrier movable between the magazine and the barrel for transferring a bullet from the magazine to the barrel, said carrier having 40 means whereby it is positively moved in opposite directions by engagement with parts of the air chamber, and means to move the air chamber.

15. In a gun or rifle, a barrel, a receiver 45 connected with the barrel, an air chamber mounted within the receiver to move longitudinally toward and away from the barrel, a plunger within the air chamber, a spring to force the plunger forwardly, means for holding the plunger in the rear position for 50 compressing the spring, means to move the air chamber longitudinally, a carrier connected with the receiver and movable into and out of proximity to the rear end of the barrel, means to effect the movement of the carrier, and an ejector connected with the carrier and adapted to move forwardly to enter the rear end of the barrel to properly 55 seat a bullet therein, and means for effecting the longitudinal movement of the ejector with relation to the carrier.

16. In an air gun or rifle, a barrel, a receiver connected with the barrel, a magazine associated with the barrel and having 60 its rear end arranged in cooperative rela-

tion to the rear end of the barrel, an air chamber arranged within the receiver and movable longitudinal toward and away from the rear end of the barrel, means to move the air chamber, a plunger within the air 70 chamber, a spring to force the plunger forwardly, means to hold the plunger in the rear position to compress the spring, a movable carrier connected with the receiver and adapted to travel between the rear ends of 75 the magazine and the barrel, said carrier having a pocket for the reception of the bullet from the magazine, a ejector mounted upon the carrier and operating within the pocket and adapted to move forwardly to 80 seat the bullet in the rear end of the barrel when the carrier is in proximity to the same, means to move the carrier, and means to move the ejector.

17. In an air gun or rifle, a barrel, a receiver connected with the barrel, a magazine associated with the barrel and having its rear end arranged in cooperative relation to the rear end of the barrel, an air chamber arranged within the receiver 90 and movable toward and away from the rear end of the barrel, means to move the air chamber, a plunger mounted within the air chamber, a spring to force the plunger forwardly, means to hold the plunger in the 95 rear position, a movable carrier connected with the receiver and having a pocket for receiving a bullet from the magazine, means to move the carrier so that its pocket may be brought into proximity with the rear ends 100 of the magazine and barrel, a movable keeper connected with the carrier for retaining the bullet within the pocket, a movable ejector connected with the carrier to force the bullet from the pocket into the rear end 105 of the barrel, and means for moving the keeper and ejector.

18. In an air gun or rifle, a barrel, a receiver connected with the barrel, spring actuated air compressing mechanism mounted within the receiver and embodying an air chamber movable toward and away from the rear end of the barrel, a transversely movable carrier arranged near the rear ends 110 of the barrel and magazine and having a pocket for the reception of a bullet from the magazine, means for effecting the transverse movement of the carrier so that its pocket may be brought into proximity to the rear ends of the barrel and magazine, a keeper movably mounted upon the carrier and projecting into the pocket to retain the bullet therein, an ejector mounted upon the carrier and movable into the pocket to force the bullet from the pocket, and means 115 to move the keeper and ejector.

19. In an air gun or rifle, a barrel, a magazine, a receiver connected with the barrel, spring actuated air compressing mechanism mounted within the receiver and embodying 120

an air chamber movable toward and away from the rear end of the barrel, a pivoted carrier arranged near the rear ends of the barrel and magazine for movement into proximity to the same and having a pocket for receiving a bullet, a pivoted keeper connected with the carrier and projecting in advance of the bullet within the pocket, a reciprocating ejector movable through the pocket to force the bullet therefrom into the rear end of the barrel, means to move the pivoted keeper, and means to move the ejector.

20. In an air gun or rifle, as a subcombination, a movable carrier having a pocket for receiving a bullet, a movable keeper connected with the carrier and having a part projecting in advance of the bullet, a movable ejector to force the bullet from the pocket, means to move the keeper, and means to move the ejector.

21. In an air gun or rifle, as a subcombination, a movable carrier having a pocket for receiving a bullet, a movable keeper connected with the carrier and having a part projecting in advance of the bullet within the pocket, a movable ejector to force the bullet from the pocket, means to move the keeper, means to move the ejector, and means operated upon the operation of the ejector for also moving the keeper.

22. In an air gun or rifle, as a subcombination, a movable carrier having a pocket for receiving a bullet, a pivoted keeper connected with the carrier and having a part projecting in advance of the bullet in the pocket, said keeper having a tail, a plunger movable within the pocket to force the bullet therefrom, a pivoted lever connected with the plunger to move it and carrying a part to engage with a portion of said tail to move the pivoted keeper, a link connected with the lever to move it, and means to engage with said tail to move the pivoted keeper and to move the link.

23. In an air gun or rifle, as a subcombination, a movable carrier having a pocket for receiving a bullet, a pivoted keeper for the pocket, an ejector operating within the pocket, a cam element connected with the keeper, a pivoted lever for operating the ejector and having a part arranged to engage a portion of the cam element, a link connected with the lever and having a shoulder, a latch device for locking the link against movement, and common means to engage a portion of said cam element for operating the keeper and also to engage the latch device for releasing the link and subsequently engaging the shoulder for moving the link in one direction.

24. In an air gun or rifle, as a subcombination, a movable carrier having a pocket for receiving a bullet and also having sides provided with longitudinal slots, the wall

of one slot having a notch, a keeper pivotally connected with the carrier, a cam element connected with the keeper, an ejector operating within the pocket, a pivoted lever for operating the ejector and having a part to engage a portion of the cam element to move the keeper, a link connected with the lever and extending longitudinally of one side of the carrier and provided with a shoulder extending across the slot of said side, a spring pressed latch pivoted to the link and having a lateral extension normally projecting across the slot, said latch embodying a pin to enter the notch in the side and having a second shoulder extending across said slot when the latch is raised, a longitudinally movable link, and a transverse pin carried by said link and slidable within said slots, said transverse pin being adapted to engage a portion of the cam element and to also engage the shoulders of the latch and the shoulder of the link.

25. In an air gun or rifle, a barrel, a receiver connected with the barrel, a magazine associated with the barrel, an air chamber movable longitudinally of the receiver toward and away from the barrel, a plunger within the air chamber, a spring to move the plunger forwardly, means for holding the plunger in the rear position for compressing the spring, means for effecting the longitudinal movement of the air chamber, a transversely movable carrier pivoted within the receiver and provided with a pocket for the reception of a bullet, said carrier having sides provided with longitudinal slots, means whereby the carrier is turned upon its pivot upon the longitudinal movement of the air chamber, a keeper pivotally connected with the carrier and having a cam element, a plunger operating within the pocket, a lever pivoted to the carrier to move the plunger and having a part to engage a portion of the cam element to move the keeper, a link connected with the lever and extending longitudinally of one side of the carrier and having a shoulder extending across the slot of said side, a latch device carried by the link and having a plurality of shoulders adapted to extend across said slot, a link having pivotal connection with the air chamber for movement therewith, and a transverse pin carried by the last named link and operating within said slots and adapted to engage with a portion of said cam element and with the shoulders of said latch and with the shoulder of the link operating said lever.

26. In an air gun or rifle, a barrel, a receiver connected with the barrel, a magazine associated with the barrel, spring actuated air compressing mechanism mounted within the receiver embodying an air chamber movable toward and away from the rear end of the barrel, a movable carrier dis-

posed in the rear of the barrel and traveling between the rear ends of the barrel and magazine, said carrier having a pocket for the reception of a bullet, a movable keeper secured to the carrier, a movable ejector secured to the carrier, means to move the keeper to the releasing position, means to normally lock the ejector against movement, means for releasing the locking means and 10 effecting the movement of the ejector, means operated upon the forward movement of the ejector to move the keeper to the releasing position, and means whereby the carrier is moved upon the longitudinal movement of 15 the air chamber.

27. In an air gun or rifle, a barrel, a receiver connected with the barrel, a magazine associated with the barrel, spring actuated air compressing mechanism mounted 20 within the receiver embodying an air chamber movable toward and away from the rear end of the barrel, a movable carrier disposed in the rear of the barrel and traveling between the rear ends of the barrel and 25 magazine, said carrier having a pocket for the reception of a bullet, a movable keeper secured to the carrier, a movable ejector secured to the carrier, means to move the keeper to the releasing position, means to normally lock the ejector against movement, means for releasing the locking means and 30 effecting the forward movement of the ejector, means operated upon the forward movement of the ejector to move the keeper to the releasing position, means to feed the 35 bullets from the rear end of the magazine, a stop to normally prevent the discharge of each bullet from the magazine, means whereby the stop is automatically moved to the releasing position when the keeper is shifted to the releasing position, and means whereby the carrier is moved upon the movement of the air chamber.

28. In an air gun or rifle, a barrel, a receiver connected with the barrel, a magazine associated with the barrel, spring actuated air compressing mechanism mounted within the receiver embodying an air chamber movable toward and away from the rear end of the barrel, a movable carrier disposed in the rear of the barrel and coacting with the rear ends of the barrel and magazine, said carrier having a pocket for the reception of a bullet, a movable keeper secured to the carrier, a movable ejector secured to the carrier, means to move the keeper to the releasing position, means for preventing improper movement of the ejector, means for effecting the proper movement of the ejector, means operated upon the forward movement of the ejector to move the keeper to the releasing position, a stop to normally prevent the discharge of each bullet from the magazine, means whereby the stop is shifted to the releasing position, and means where-

by the carrier is moved upon the movement of the air chamber.

29. In an air gun or rifle, a barrel, a receiver connected with the barrel, a magazine associated with the barrel, spring actuated air compressing mechanism mounted within the receiver embodying an air chamber movable toward and away from the rear end of the barrel, a carrier movable transversely of the rear ends of the barrel and 70 magazine and having a pocket for receiving a bullet, a movable keeper secured to the carrier, a movable ejector secured to the carrier, means to move the keeper to the releasing position, means for holding the ejector against accidental movement and for effecting its proper movement, means operated upon the forward movement of the ejector to move the keeper to the releasing position, means whereby the bullets are 75 properly fed from the rear end of the magazine, a movable spring actuated stop adapted to move inwardly to engage and hold the bullet in the magazine, said stop having a part arranged in the path of travel of the 80 keeper to be automatically shifted thereby, and means whereby the carrier is moved upon the movement of the air chamber.

30. In an air gun or rifle, a barrel, a receiver connected with the barrel, a magazine associated with the barrel, spring actuated air compressing mechanism mounted within the receiver embodying an air chamber movable toward and away from the rear end of the barrel, a carrier movable transversely of the rear ends of the barrel and magazine and having a pocket for receiving a bullet, a movable keeper secured to the carrier, a movable ejector secured to the carrier, means to move the keeper to the releasing position, means for holding the ejector against accidental movement and for effecting its proper movement, means operated upon the forward movement of the ejector to move the keeper to the releasing position, a spring pressed follower mounted to move longitudinally within the magazine and having a head substantially corresponding in shape and size to the bullets, a movable spring actuated stop having a part provided with a recess corresponding in shape and size to the bullet and head and automatically moving inwardly toward the magazine when released, said stop having a part arranged in the path of travel of the keeper to be automatically shifted thereby, and means whereby the carrier is moved upon the longitudinal movement of the air chamber.

31. In an air gun or rifle, a barrel, a receiver, a magazine associated with the barrel, spring actuated air compressing mechanism mounted within the receiver embodying an air chamber movable toward and away from the rear end of the barrel and a

spring to be compressed, means to transfer a bullet from the magazine to the barrel, and automatic means for rendering it impossible to compress the spring of said mechanism after the last bullet in the magazine has been fed into the barrel and fired from the barrel.

32. In an air gun or rifle, a barrel, a receiver, a magazine associated with the barrel, spring actuated air compressing mechanism mounted within the receiver embodying a spring pressed plunger and an element connected with the plunger, a sear adapted to have holding engagement with said element, means to transfer a bullet from the magazine to the barrel, and means automatically operated upon the feeding of the last bullet from the magazine to the barrel and the firing of the same from the barrel, for controlling the operation of the sear so that it cannot have holding engagement with the plunger element.

33. In an air gun or rifle, a barrel, a receiver, a magazine associated with the barrel, spring actuated air compressing mechanism mounted within the receiver embodying a spring pressed plunger and an element connected therewith, a self releasing sear adapted to have holding engagement with said element, a trigger adapted when engaging with the sear to hold the same against releasing movement, and means automatically operated upon the feeding of the last bullet from the magazine to the barrel and the firing of the same, to hold the trigger against moving into engagement with the sear.

34. In an air gun or rifle, a barrel, a receiver, a magazine associated with the barrel, spring actuated air compressing mechanism mounted within the receiver embodying a spring pressed plunger and an element connected therewith, means for feeding the bullets from the magazine to the barrel, a self releasing sear adapted to have holding engagement with said element, a trigger adapted when engaging the sear to hold the same against releasing movement, a spring pressed follower mounted within the magazine to feed the bullets from the same and having a head corresponding in shape and size to the bullets and also having a shoulder, a movable stop element arranged near the magazine and having a part provided with a recess corresponding in shape and size to the bullet and head, means carried by the feeding means to automatically shift the stop element to the outer position, said stop element being held in the intermediate position by engagement with the shoulder of the spring pressed follower, and a pivoted lever engaging the movable stop and having a part adapted to engage with the trigger when the stop is being held in the intermediate position.

35. In an air gun or rifle, a barrel, a receiver connected therewith, a magazine associated with the barrel, spring actuated air compressing mechanism mounted within the receiver embodying an air chamber movable toward and away from the rear end of the barrel, a carrier movable transversely of the rear ends of the barrel and magazine and having a pocket for receiving a bullet, a movable keeper secured to the carrier, a movable ejector secured to the carrier, means to move the keeper to the releasing position, means for holding the ejector against accidental movement and for effecting its proper movement, means operated upon the forward movement of the ejector to move the keeper to the releasing position, a spring pressed follower mounted within the magazine, a movable stop arranged near the discharge end of the magazine and adapted to engage with the bullet discharging therefrom, said stop having a part arranged in the path of travel of the keeper, a manually operated stop arranged near the discharge end of the magazine and adapted to operate independently of the first named stop to prevent the discharge of bullets from the magazine, and means whereby the carrier is moved upon the longitudinal movement of the air chamber.

36. In an air gun or rifle, a barrel, a receiver connected with the barrel, a magazine associated with the barrel, spring actuated air compressing mechanism carried by the receiver embodying a spring pressed plunger, having a holding element, means for feeding the bullets from the magazine to the barrel, a sear adapted to have holding engagement with said holding element, a trigger for coaction with the sear, a spring pressed follower mounted within the magazine to feed the bullets from the same and having a head corresponding in shape and size with the bullets and also having a shoulder, an automatic stop element arranged near the discharge end of the magazine and having a part provided with a recess corresponding in shape and size to the bullet and head, said stop element being held in the intermediate position by engagement with the shoulder of the spring pressed follower, means operated by the automatic stop when in the intermediate position for holding the trigger out of holding engagement with the sear, and a manually operated stop arranged near the discharge end of the magazine and adapted to be moved inwardly and forwardly with respect to the magazine, said manually operated stop being adapted when the last bullet is discharged from the magazine to engage with the head of the follower and retain the same in a sufficiently forward position so that it will be received within the recess of the automatic stop when the stop moves inwardly.

37. In an air gun or rifle, a barrel, a receiver connected with a barrel, a magazine associated with the barrel, air compressing mechanism embodying a spring to be placed under compression, a spring-pressed follower within the magazine to discharge the bullets therefrom, a carrier to feed the bullets from the magazine to the barrel, an automatic stop to engage with the bullet 5 at the discharge end of the magazine when the preceding bullet is being transferred to the barrel, said follower being so constructed that it is adapted to retain the automatic stop in the intermediate position when the 10 follower is in the extreme rear position and engaged by the automatic stop, means actuated by the automatic stop when in the intermediate position to render it impossible to compress the spring of the air compression mechanism, and manually operated stop 15 means adapted to engage with the follower and shift it forwardly sufficiently so that its engagement with the automatic stop will permit of the automatic stop assuming the 20 inner position.
38. In an air gun or rifle, a barrel, a receiver connected with the barrel, spring actuated air compressing mechanism embodying a reciprocatory air chamber movable longitudinally toward and away from the rear end of the barrel, and a substantially air tight joint between the forward end of the air chamber and the rear end of the barrel, said joint embodying telescoping 25 parts arranged wholly exteriorly of the bore of the barrel whereby the bore is free from obstruction.
39. In an air gun or rifle, a barrel, a receiver connected with the barrel, a spring actuated air compressing mechanism embodying reciprocatory air chamber movable longitudinally toward and away from the barrel, a tubular extension arranged at the 30 rear end of the barrel and having a bore of the same diameter as the bore of the barrel and forming a continuation thereof, and a tubular socket formed upon the forward end of the air chamber and receiving the tubular extension therein, said tubular socket being arranged wholly exteriorly of the bore 35 of the tubular extension so that said bore is unobstructed.
40. In an air gun or rifle, a barrel, provided at its rear end with a tubular extension, the bore of the barrel extending unobstructed through said tubular extension, a spring actuated air compressing mechanism embodying a reciprocatory air chamber movable longitudinally toward and away 40 from the rear end of the barrel and provided at its forward end with an inwardly extending tubular socket within which the tubular extension telescopes, said tubular socket being arranged wholly exteriorly of the bore 45 of the barrel.
41. In an air gun or rifle, a barrel provided at its rear end with a tubular extension with the bore of the barrel extending unobstructed through said tubular extension, a spring actuated air compressing mechanism embodying an air chamber movable longitudinally toward and away from the rear end of the barrel and provided at its forward end with a tubular socket within which the tubular extension telescopes with 50 the tubular socket arranged exteriorly of the bore of the barrel whereby said bore is wholly unobstructed, and a yielding packing element arranged between the rear end of the barrel and the forward end of the air 55 chamber.
42. In an air gun or rifle, a barrel, a receiver connected with the barrel, spring actuated air compressing mechanism embodying an air chamber movable longitudinally toward and away from the rear end of the barrel, a substantially air tight joint between the forward end of the air chamber and the rear end of the barrel, said joint embodying telescoping parts arranged 60 wholly exteriorly of the bore of the barrel whereby the bore is free from obstruction, a magazine for holding a plurality of bullets, a movable carrier to transfer a bullet from the magazine to the barrel, and a movable ejector mounted upon the carrier and adapted to move into the rear end of the barrel to properly seat the bullet therein.
43. In an air gun or rifle, a barrel provided at its rear end with a tubular extension, the bore of the barrel extending unobstructed through the tubular extension, a receiver connected with the barrel, spring actuated air compressing mechanism embodying an air chamber movable longitudinally within the receiver toward and away from the rear end of the barrel and provided at its forward end with an inwardly extending tubular socket within which the tubular extension telescopes, said tubular socket being arranged wholly exteriorly of the bore of the barrel, a magazine for holding a plurality of bullets, a carrier to transfer the bullets from the magazine to the barrel, and a movable ejector mounted upon the carrier to properly seat the bullets within the barrel.
44. In an air gun or rifle, a barrel, a receiver carrying the barrel, spring actuated air compressing mechanism coacting with the barrel, a movable sear for controlling the operation of said mechanism, a trigger to control the operation of said sear, adjustable means to regulate the pull of the trigger for obtaining a selected light pull, and graduated adjustable means for obtaining a plurality of pulls heavier than the first selected light pull.
45. In an air gun or rifle, a barrel adapted to be loaded from its rear end, a receiver 130

carrying the barrel and having an opening whereby the bullets may be manually introduced into the rear end of the barrel, an air chamber movable longitudinally within the receiver and provided near its rear end with an abutment movable therewith, a plunger within the air chamber, a spring arranged within the rear portion of the air chamber between the plunger and the abutment of the air chamber, a plunger rod connected with the plunger and extending to the exterior of the air chamber, the air chamber, the plunger, and spring moving as a unit rearwardly whereby the spring is not compressed when the air chamber is in the rear position and the opening in the receiver uncovered for the introduction of the bullets into the rear end of the barrel, means for holding the plunger rod against forward movement with respect to the air chamber whereby the spring is compressed as the air chamber is moved forwardly into proximity to the rear end of the barrel and for covering the opening in the receiver, and means for effecting the longitudinal movements of the air chamber.

46. In an air gun or rifle, a barrel, a receiver connected with the barrel and extending rearwardly therefrom, a stock connected with the receiver, an air chamber slidable longitudinally within the carrier toward and away from the rear end of the barrel, a plunger within the air chamber, a compressible coil spring within the air chamber rearwardly of the plunger, an abutment carried by the rear portion of the air chamber and engaging the rear end of the spring, means for holding the plunger against forward movement when the air chamber is moved forwardly for placing the spring under compression, a lever extending generally longitudinally of the receiver and stock when in the cocked position and pivotally connected between its ends with the receiver, and a link pivotally connected with the forward end of the lever and with the air chamber, the parts being so arranged that when the lever is in the cocked or closed position the air chamber is shifted to its forwardmost position and the pivotal connection between the link and lever is upon one side of the pivotal support of the lever whereby such lever and associated elements are automatically locked against movement with the lever in close relation with the stock.

47. In an air gun or rifle, a barrel, a receiver connected with the barrel and extending rearwardly therefrom, a stock connected with the receiver, an air chamber slidable longitudinally within the receiver toward and away from the rear end of the barrel, a plunger within the air chamber, a spring located within the air chamber rearwardly of the plunger, said air chamber having a

part serving as an abutment and engaging the rear end of the spring, a plunger rod connected with the plunger, means for holding the plunger rod against forward movement when the air chamber is moved forwardly whereby the spring is compressed upon the forward movement of the air chamber, a compressible packing element arranged near the rear end of the barrel for engagement with the forward end of the air chamber for effecting a substantially air tight joint between the air chamber and barrel, a lever extending generally longitudinally of the receiver and stock when in the closed or cocked position and pivotally connected between its ends with the receiver, and a link pivotally connected with the forward end of the lever and pivotally connected with the air chamber, the parts being so arranged that when the lever is in the cocked or closed position the air chamber is shifted to its forwardmost position for compressing engagement with the packing thereby effecting the air tight joint between the air chamber and barrel, and the pivotal connection between the link and lever is upon the outer side of the pivoted support of the lever whereby such lever and associated elements are automatically locked against movement with the lever held in the rear position in close relation to the stock.

48. In an air gun or rifle, a barrel, a receiver, an air chamber movable longitudinally within the receiver toward and away from the barrel and having an abutment movable therewith, a plunger within the air chamber, a spring within the air chamber rearwardly of the plunger and forwardly of the abutment, a plunger rod connected with the plunger, means to hold the plunger rod against forward movement, and means to move the air chamber forwardly while the plunger rod is held against forward movement whereby the spring is compressed between the plunger and abutment.

49. In an air gun or rifle, a barrel, a receiver connected with the barrel, air compressing mechanism carried by the receiver and embodying a spring adapted to be placed under compression, a stock connected with the receiver and having a small part, an operating lever pivotally connected with the receiver and having connection with the air compressing mechanism for placing the spring under compression, said operating lever being adapted to be shifted to an inner position in close proximity to the stock, a movable sear for controlling the operation of the air compressing mechanism, a movable trigger for controlling the operation of the sear, a lock device automatically operating to hold the trigger against movement in one direction, and manually operated means mounted upon the operating

lever and adapted to be shifted by such lever when moved to the inner position, into a cooperative relation to the lock device, whereby said manually operated means may 5 then be actuated by the finger or fingers surrounding the small part of the stock for releasing said lock device.

50. In an air gun or rifle, a barrel, a receiver connected with the barrel, air 10 compressing mechanism carried by the receiver and embodying a spring adapted to be placed under compression, a stock connected with the receiver and having a small part, an operating lever pivotally connected with 15 the receiver and having connection with the air compressing mechanism for placing the spring under compression, said operating lever being adapted to be shifted to an inner position in close proximity to the stock, a 20 movable sear for controlling the operation of the air compressing mechanism, a movable trigger for controlling the operation of the sear, a lock device automatically operating to hold the trigger against movement in one direction, manually operated 25 means mounted upon the operating lever and adapted to be shifted by such lever when moved to the inner position, into a cooperative relation to the lock device, whereby 30 said manually operated means may then be actuated by the finger or fingers surrounding the small part of the stock for releasing said lock device, and manually operated 35 means arranged near the top of such small part of the stock and adapted to render the first named manually operated means incapable of releasing the lock device when the operating lever is in the inner position.

51. In an air gun or rifle, a barrel 40 provided at its rear end with a tubular extension with the bore of the barrel extending therethrough, an air chamber at the rear of the barrel and having its forward end provided with a tubular socket arranged exteriorly of the tubular extension and wholly exteriorly of the bore of the barrel, a hard fiber washer arranged adjacent the rear end of the tubular socket, and a plurality of resilient washers arranged in advance of the 45 hard fiber washer, said resilient washers increasing in resiliency forwardly, a plunger in the air chamber, a spring to force the plunger forwardly, and means to control the forward movement of the plunger.

52. In an air gun or rifle, a barrel, an air 55 chamber at the rear of the barrel, a plunger to slide in the air chamber, a spring to move the plunger forwardly, means to control the forward movement of the plunger, a hard fiber washer mounted within the forward 60 portion of the air chamber to receive the impact from the plunger and having an opening formed therein of substantially the same diameter as the bore of the barrel, and relatively resilient packing arranged between the hard fiber washer and the forward 65 end of the air chamber.

53. In an air gun or rifle, a barrel provided at its rear end with a tubular extension with the bore of the barrel extending 70 therethrough, an air chamber at the rear of the barrel and having its forward end provided with a rearwardly projecting tubular socket adapted for receiving the tubular extension therein, said tubular socket being 75 disposed exteriorly of the tubular extension and wholly exteriorly of the bore of the barrel, a non-metallic relatively hard washer arranged adjacent the rear end of the tubular socket and having an opening formed 80 therein in registration with the bore of the barrel, said opening being of substantially the same diameter as the bore of the barrel forming in effect an unobstructed continuation of said bore, yielding backing arranged 85 in advance of the non-metallic washer and disposed exteriorly of said tubular extension whereby such backing cannot enter the exterior of the tubular extension, a plunger in the air chamber, a spring 90 to force the plunger forwardly, and means to control the forward movement of the 95 plunger.

54. In an air gun or rifle, a barrel, a receiver associated with the barrel, an air 95 chamber movable in the direction of its length within the receiver and having an abutment movable therewith, a plunger within the air chamber, a spring within the air chamber to be compressed between 100 the plunger and the abutment, means to hold the plunger against longitudinal movement in one direction, and means to move the air chamber longitudinally while the plunger 105 is being held against longitudinal movement for compressing the spring.

In testimony whereof I affix my signature.
MYRON R. RANDALL.
